[57] CLAIM

The ornamental design for a rack, as shown and described.

DESCRIPTION

FIG. 1 is a top, front and right side perspective view of a rack showing my new design;

FIG. 2 is a bottom plan view thereof;

FIG. 3 is a front elevational view thereof; and,

FIG. 4 is a right side elevational view thereof, the left side being a mirror image of that shown.

The broken-line disclosure is for illustrative purposes only and forms no part of the claimed design.
